INSULATING COVERING FOR AN ELECTRIC TERMINAL CONNECTOR

Willard LeRoy Busler, Harrisburg, Pa., assignor to
AMP Incorporated, Harrisburg, Pa.

Filed Feb. 27, 1964, Ser. No. 78,804

Term of patent 14 years

(Cl. D26—10)

FIGURE 1 is a front, top and right end perspective view of an insulating covering for an electric terminal connector, showing my new design;

FIGURE 2 is a right side elevational view;

FIGURE 3 is a left side elevational view;

FIGURE 4 is a top plan view;

FIGURE 5 is a bottom plan view;

FIGURE 6 is a front elevational view; and

FIGURE 7 is a rear elevational view thereof.

The broken line showing of a wire stub in FIGURES 2, 4, 5 and 6 and of terminal prongs in FIGURE 6 are for illustrative purposes only.

I claim:

The ornamental design for an insulating covering for an electric terminal connector, as substantially shown and described.
